(57) CLAIM

The ornamental design for a duvet cover having edge pleats and piping as shown and described.

DESCRIPTION

FIG. 1 is a front perspective view of a duvet cover having edge pleats and piping, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged, sectional, and perspective view taken from the encircled area 8 in dot-dash line in FIG. 1, showing the edge pleats and piping in a flat position; and,

FIG. 9 is an enlarged, sectional, and perspective view thereof, showing the edge pleats and piping in an alternate raised position.

The dash-dash lines in FIGS. 1, 6, 7, 8 and 9 indicate stitching.

1 Claim, 5 Drawing Sheets
